UNITED STATES PATENT OFFICE.

ALBERT T. SCHLICHTING AND JULIUS SMITH, OF BROOKLYN, ASSIGNEES
OF THREE-FIFTHS TO ADOLPH KERN, OF NEW YORK, N. Y.

FRUIT-JAR.

SPECIFICATION forming part of Letters Patent No. 428,703, dated March 18, 1890.

Application filed July 31, 1889. Serial No. 319,317. (No model.)

To all whom it may concern:

Be it known that we, ALBERT T. SCHLICHTING and JULIUS SMITH, both of Brooklyn, Kings county, New York, citizens of the 5 United States, have invented certain new and useful Improvements in Fruit-Jars, of which the following is a specification.

The object of our invention is to provide a new and improved fruit-jar which is simple 10 in construction, can readily be opened and closed, forms an absolutely tight seal, and the contents of which can under no circumstances be contaminated by coming in contact with metal.

15 The invention consists in the construction and combination of parts and details, as will be fully described and set forth hereinafter, and then pointed out in the claim.

In the accompanying drawings, Figure 1 is 20 a vertical transverse sectional view of our improved fruit-jar, parts of the jar being broken out. Fig. 2 is a plan view of the same, parts being broken out.

Similar letters of reference indicate corresponding parts.

25 The fruit-jar A, which may be made of glass, earthenware, or any other suitable material, is provided with the exteriorly screw-threaded neck B. At the bottom of said neck an internal annular shoulder C is formed, which is beveled from the inner surface of the neck inward and downward. The inner cover D is made of porcelain or glass and is provided 30 at the bottom of its edge with a downwardly and inwardly beveled annular shoulder E and with a raised rim F, having a flat annular top. The said inner cover is also provided with a handle-button G, projecting upward from the center of the top recess in said 35 cover. The outer sheet-metal cover H is provided with a screw-threaded flange J, that can be screwed on the threaded neck B of the jar. On the under side of the said sheet-metal outer 40 cover H an annular downwardly-projecting bead K is formed, which can bear on the upper flat edge of the raised annular rim F of the inner cover D.

45 After the jar has been filled a packing-ring or gasket L, of india-rubber, is placed upon the beveled shoulder C of the jar, and the inner porcelain cover D is placed into the

neck of the jar in such a manner that the bevel E of said inner cover rests upon the gasket L. The outer sheet-metal cover H is then screwed on the neck of the jar, and its 55 annular bead K, pressing on the raised rim F of the inner cover D, presses the bevel of said inner cover against the gasket L and in turn the gasket against the annular bevel C of the jar, thereby forming an absolutely tight joint 60 and seal.

The contents of the jar can under no circumstances come in contact with metal, either when filling or emptying the jar, and thus all danger of contaminating the contents of 65 the jar is avoided. The covers can be applied or removed very easily and rapidly, and the gasket is not subjected to any twisting strain while screwing on the metal cover, as it is in fruit jars in which the gasket is placed 70 between the surface of the jar and a flange of said cover.

We are aware that interior porcelain or glass covers and exterior metal covers and packing-rings have been used on fruit-jars, 75 and do not claim this, broadly, as our invention; but,

Having fully described our invention, what we claim as new, and desire to secure by Letters Patent, is—

80 The combination, with a fruit-jar having an externally-screw-threaded neck and a downwardly and inwardly beveled interior annular shoulder at the bottom of the neck, of an interior porcelain cover provided with 85 an annular bevel at the bottom of its edge and an upwardly-projecting rim having a flat top, a metal screw-cover adapted to be screwed on the neck of the jar and provided on its under side with an annular projection which 90 presses on the raised rim of the inner cover, and a gasket between the inner cover and jar, substantially as herein shown and described.

In testimony that we claim the foregoing as 95 our invention we have signed our names in presence of two subscribing witnesses.

ALBERT T. SCHLICHTING.
JULIUS SMITH.
